UNITED STATES PATENT OFFICE.

STEPHEN P. M. TASKER, OF PHILADELPHIA, PENNSYLVANIA.

MANDREL.

SPECIFICATION forming part of Letters Patent No. 331,578, dated December 1, 1885.

Application filed July 22, 1885. Serial No. 172,976. (No model.)

To all whom it may concern:

Be it known that I, STEPHEN P. M. TASKER, a citizen of the United States, residing in the city and county of Philadelphia, and State of Pennsylvania, have invented a new and useful Improvement in Mandrels, of which the following is a specification.

My invention relates to the class of mandrels which are known as "roller-mandrels," and which are provided with ellipsoidal friction-rolls mounted in bearings in a stock or case, such a mandrel having been invented by me and patented to me in and by Letters Patent of the United States No. 151,323, dated 15 May 26, 1874.

The intention of the employment of a mandrel of the foregoing class is to obviate friction between the interior surfaces of the tube and the ball of the mandrel, and to permit of the 20 more ready passage of the tube over the mandrel and withdrawal of the mandrel from the tube.

The object of my present invention is to provide a mandrel of the foregoing class which 25 is provided with three ellipsoidal rolls, the axes of which are arranged at an angle to each other and each roll at a common angle to its neighbor, and which rolls are adapted to be adjusted the one with respect to the other, so 30 as to change the relative inclinations of their several axes.

My mandrel is especially designed for employment in connection with a certain apparatus for manufacturing tubes and for reducing 35 and straightening metal tubes, which, briefly stated, consists of a set or a series of sets of rolls, each of which sets is composed of three concave-faced rolls arranged at an angle to each other and each roll at a common angle to 40 its neighbor, so that the concave surfaces of all of the rolls form a circular pass which surrounds a tube passed through it, the said machine constituting the subject-matter of several applications for patents executed by me and 45 filed in the Patent Office contemporaneously with this application.

Apparatus embodying a good form of my invention is represented in the accompanying drawings and described in this specification, 50 the particular subject-matter claimed as novel being hereinafter definitely specified.

In the drawings, Figure 1 is a side elevation

of a mandrel embodying my invention. Fig. 2 is a face view of the same. Fig. 3 is a rear view of the same, section being supposed 55 through the mandrel-rod in the plane of the dotted line xx of Fig. 1, and sight being taken in the direction of the arrows upon said line. Fig. 4 is a fragmentary longitudinal sectional detail taken through the stock and through 60 one of the bridles. Fig. 5 is a perspective view of the entire device. Fig. 6 is a view similar to Fig. 3, showing four rolls in the stock.

In all of the figures the rolls occupy what I 65 assume to be their normal position.

Similar letters of reference indicate corresponding parts.

In the drawings, A represents the mandrel-rod, which is a part of or connected with the 70 stock B, which is conveniently made as a triangular prism. Against the face of each parallelogram or side of the prismatic stock is applied a budge, C, conveniently made of the shape represented in the drawings, which carries or with respect to which is journaled an ellipsoidal or spheroidal roll, D. Each face or side of the mandrel stock is provided with a segmental way, b, within which is fitted a segmental lug, c, formed upon the under side 80 of the budge. A segmental slot, c^x , is formed through the budge and through the lug thereon, through which slot passes a threaded stem, E, secured to the stock and armed with a nut, e, which is adapted, when screwed down, to 85 bind the budge fixedly in any given position which it is capable of assuming with respect to the face of the prism or stock to which it is applied. It will be obvious that by virtue of the segmental ways and segmental lugs 90 fitted thereto each budge is capable of being adjusted with respect to the stock. The rolls are mounted in the cheek-pieces of the budge by means of journals d, which are either secured to the rolls and play in suitable bearings in the cheek-pieces of the budge, or else are secured to said cheek-pieces of the budge and are entered within suitable bearings 95 formed in the rolls. Each budge is, as shown in Fig. 3, of greater thickness at one side than at the other, so as to impart a pitch to the axis of its roll, and thereby occasion the disposition of said axis at a slight angle to the plane of the side face of the stock.

As an expedient of construction, each bridle at its inner end is segmental and abuts against a segmental shoulder, b^x , formed upon the stock. The threaded stems may, if desired, be provided with fixed heads and be screwed into threaded sockets in the stock. The form of the bridles is conveniently that shown. It may, however, be modified. It is, however, essential that the cheek-pieces of the bridles, to which the journals of the rolls are applied, should be rounded, as shown in Figs. 2 and 3, so as to lie below a circle circumscribing the three rolls in the region of their greatest diameter, in order that the bridles may not touch the tube as it is passed over the mandrel.

Having thus described a good construction of my device, it will be obvious that each roll is capable of an independent adjustment with respect to both of the other rolls, and that by means of this adjustment the axis of each of the rolls may be inclined from a line which is right angular to the longitudinal axis of the mandrel and stock. In whatever position the rolls are adjusted, they bear upon each other near their ends, so that the inward thrust upon them is taken off their journals and borne upon their rolling-surfaces.

In employing my said mandrel with a set of three angularly-disposed concave-faced rolls, the axes of which are correspondingly inclined to each other, the mandrel is to be inserted in the pass of the rolls, and the rolls of the mandrel are to be adjusted so that their respective axes are parallel with the axes of the rolls of the mill in connection with which they respectively operate, and when the said rolls of the mill are adjusted a similar adjustment to preserve the parallelism of the axes is to be made in the rolls of the mandrel.

I contemplate employing a series of mandrels of this class in connection with a series of rolls of the class referred to.

It is obvious that, if desired, the frames or bridle can be so set that the rolls are parallel, that the mandrels can be employed in connection with dies instead of rolls, and that they are adapted to be used for the rolling of metal either hot or cold.

Instead of the threaded stems and nuts, other means for retaining the bridles in the different adjusted positions may of course be resorted to.

It is also obvious that by making the prismatic stem quadrangular, and by suitably proportioning the rolls, the device is adapted to be provided with four rolls and bridles, as shown in Fig. 6, or to be correspondingly fitted with a greater number than four rolls.

In fact, the number of the series of rolls is not essential, so long as the series be composed of three or more rolls.

The segmental ways and lugs are convenient devices to insure accurate adjustment; but they may be omitted, or, if desired, other kindred constructions resorted to in their stead.

Having thus described my invention, I claim—

1. The combination, in a roller-mandrel, of a series of three or more ellipsoidal rolls, the axes of which are inclined to each other, substantially as set forth.

2. The combination, in a roller-mandrel, of a series of three or more ellipsoidal rolls, the axes of which are inclined to each other, bridles for supporting the rolls, and a stock to which the bridles are connected, substantially as set forth.

3. The combination, in a roller-mandrel, of a series of three or more ellipsoidal rolls, the axes of which are inclined to each other, bridles for supporting the rolls, a stock to which the bridles are connected, and means for adjusting the bridles with respect to the stock, substantially as set forth.

4. The combination, in a roller-mandrel, of a prismatic stock, a series of ellipsoidal rolls, the axes of which are inclined to each other, and which correspond in number with the side faces of the stock, bridles for carrying said rolls, which are applied to the respective faces of the prismatic stock, and means for adjusting the bridles with respect to the stock, substantially as set forth.

5. The combination of the stock, the segmental ways in said stock, the bridles provided with segmental lugs and with slots, nuts provided threaded stems for effecting the retention of the bridles in different adjusted positions, and ellipsoidal rolls carried by the bridles, substantially as set forth.

6. The prismatic stock provided with the segmental ways and the segmental shoulders, in combination with the bridles, provided with the segmental lugs and with slots, and also provided with ellipsoidal rolls, and with means for securing the adjustment of the bridles with respect to the stock, substantially as set forth.

In testimony whereof I have hereunto signed my name this 17th day of July, A. D. 1885.

STEPHEN P. M. TASKER.

In presence of—

J. BONSALL TAYLOR,
JOHN JOLLEY, Jr.
